UNITED STATES PATENT OFFICE

ROGER A. SELBY, OF PORTSMOUTH, OHIO, ASSIGNOR TO THE SELBY SHOE COMPANY, OF PORTSMOUTH, OHIO, A CORPORATION OF OHIO

DESIGN FOR A SHOE

Application filed July 24, 1929. Serial No. 32,193. Term of patent 3½ years.

To all whom it may concern:

Be it known that I, ROGER A. SELBY, a citizen of the United States, residing at Portsmouth, in the county of Scioto and State of Ohio, have invented a new, original, and ornamental Design for Shoes, of which the following is a specification, reference being had to the accompanying drawing, forming part thereof.

Figure 1 is a side view of a shoe with the buckle in the open position showing my new design;

Figure 2 is a view of the opposite side of the shoe shown in Figure 1, with the buckle in a closed position.

I claim:

The ornamental design for a shoe, as shown and described.

ROGER A. SELBY.
